(57) **CLAIM**

The ornamental design for a cellular and blind shade assembly, as shown and described.

DESCRIPTION

FIG. 1 is a perspective view of the cellular and blind shade assembly according to the present design;

FIG. 2 is a front view of the cellular and blind shade assembly illustrated in FIG. 1 showing the cellular and blind shade assembly according to the present design;

FIG. 3 is a rear view of the cellular and blind shade assembly illustrated in FIG. 1 showing the cellular and blind shade assembly according to the present design;

FIG. 4 is a side view of the cellular and blind shade assembly illustrated in FIG. 1, shown from the right side and showing the cellular and blind shade assembly according to the present design;

FIG. 5 is a side view of the cellular and blind shade assembly illustrated in FIG. 1, shown from the left side and showing the cellular and blind shade assembly according to the present design; and,

FIG. 6 is a top view of the cellular and blind shade assembly illustrated in FIG. 1 showing the cellular and blind shade assembly according to the present design.

The claimed design comprises the elements shown in solid lines. The broken lines in the drawings represent environmental subject matter that forms no part of the claimed design. Additionally, the cellular and blind shade assembly is shown with symbolic breaks in width and length. The appearance of any portion of the article between the break lines forms no part of the claimed design. The broken lines form no part of the claimed design.
